UNITED STATES PATENT OFFICE.

CARL G. NORMAN, OF CHICAGO, ILLINOIS.

SANDPAPERING MACHINE.

1,406,275.

Specification of Letters Patent. Patented Feb. 14, 1922.

Application filed April 11, 1918, Serial No. 227,896. Renewed October 22, 1921. Serial No. 509,529.

To all whom it may concern:

Be it known that I, CARL G. NORMAN, a citizen of the United States, residing at Chicago, in the county of Cook and State of Illinois, have invented a certain new and useful Improvement in Sandpapering Machines, of which the following is a full, clear, concise, and exact description, reference being had to the accompanying drawings, forming a part of this specification.

My invention relates to sand papering machines, and has to do with the provision of means for resiliently carrying the abrasive material so that an even polish of floors or other surfaces to be finished may be secured.

With the use of the devices of the prior art, which were ordinarily provided with a drum having sand paper disposed over the outside of the drum but having no resilient means between the sand paper and the drum, a smooth finish could be obtained only by an experienced operator for the reason that during the rotation of the drum contact with the floor was made only along a single line. Unless movement of the rotating drum across the floor was maintained constantly, grooves resulted due to the rotation of the drum in a single position. Frequently padding, such as felt, would be placed between the sand paper and the drum but after a short time the padding would pack with the result that its usefulness would be destroyed.

Another objection to these devices is the constant vibration of the entire machine as the rotating drum engages the floor.

Broadly, my invention comprises a drum, or a pair of drums, having a plurality of leaf springs secured to the outer side, each of the spring members having a free end pointing away from the direction of the rotation of the drum so that centrifugal force will cause the free ends of the spring members to move outwardly and as the springs engage the floor or surfaces to be polished a contacting surface of about three or four inches is obtained when a drum of about twelve inches in diameter is used. I have found that substantially the same operation is effected as is obtained by hand sand papering, and this is manifested by the character of the shavings which are long and shred-like as distinguished from the dust which ordinarily results from the use of sand papering machines in use heretofore.

My invention will be understood more

clearly by reference to the accompanying drawings, in which—

Figure 1 is a side view of my improved sand papering machine;

Figure 2 is a horizontal sectional view showing parts of the mechanism in section and parts in elevation;

Figure 3 is a perspective view of the drums supporting the springs and abrasive material. This view also shows the fan mechanism for drawing the shavings from within the housing and directing the same through a chute leading to a receiving receptacle;

Figure 4 is a perspective view of one of the leaf springs used for supporting the abrasive material; and

Figure 5 is a detail view showing the method of adjusting the machine.

Similar characters of reference refer to similar parts throughout the several views.

As seen in Figure 1, the machine comprises a housing 10 mounted on a pair of wheels 11—11 and adjustable rollers 12—12 by means of which the abrading elements may be adjusted relative to the surface to be finished. A motor 13 is mounted on the housing and connected to a shaft 14 by means of a chain 15 passing over a gear 16 keyed or otherwise secured to the shaft. The shaft 14, preferably, is mounted in ball bearings carried by the housing to secure easy and noiseless operation. The machine is moved over the floor by means of a handle 17 on which can be located a switch 18 for controlling the electric current necessary for operating the motor 13. Within the housing 10 and mounted upon the shaft 14 is a pair of drums 19 and 20 which are similar in construction. These drums are secured to the shaft 14 by means of set screws 21 passing through the hubs of the drums and engaging the shaft 14. Each of the drums 19 and 20 has a flanged portion 22 and 23 provided with an annular groove 24 and 25 into which extend the edges of a ring 26 supported by arms 27 connecting the inner side of the ring 26 to the hub 29 disposed around the shaft 14. Ball bearings 31 and 32 are provided in each end of the hub 29 through which the shaft 14 passes. The ring 26 is stationary and is provided with an opening 34 through which passes the chute of sheet metal 35 communicating with a dust box 36.

Although it would be possible to employ

one rotatable drum I have found it desirable to employ two for the reason that irregularities in the floor level are accommodated more satisfactorily. The chief object of the ring 26 is to provide a means for effecting a single chamber within the drum so that the shavings can be controlled.

Within the drums 19 and 20 I have arranged fan members 38 and 39 arranged to

10 cause a circulation of air within the housing of the machine whereby the shavings and dust resulting from a polishing operation are directed through the chute 35 and into the box 36.

14 The drums 19 and 20 are each provided with a plurality of fixtures 40 secured to the outside of the drums by means of the screws 41. The screws 41 extend upwardly beyond the outer side of the fixtures, the 20 object of which will appear presently. The fixtures 40 are each bent upwardly at 42 to receive one end of an arcuate spring member 43 secured to the portion 42 by means of bolts. The end portion of the spring 43

25 is bent upon itself, as illustrated at 44, to provide a resilient abutment for the spring 43 in operation. A padding of felt 46 is disposed over each spring 43 and held in place by a clamping member 47 which is provided with a pair of keyhole slots 49—49, the enlarged opening 50 of which is arranged to be slipped over the heads of the screws 41.

35 The abrasive means consists of a piece of canvas or other heavy cloth 52 on one side of which is glued a sheet of sand paper or other similar material 53 terminating on portions of the canvas substantially as illustrated. In practice it has been found that 40 if sand paper alone is used the vibration at or near the free end of the spring members is such as to cause cracking of the paper and eventual breaking of the same. It will be seen that the sand paper terminates at about the point of greatest vibration and the strength and flexibility of the canvas permits this movement without injury. I contemplate the use of a piece of canvas having sand paper glued to one face

45 for each of the spring members 43 and to assemble the same the ends of the canvas are brought adjacent the fixtures 40, after which the clamping members 47 are slipped over the heads of the screws 41, are brought down against the canvas, and are retained in position by the inward movement of the clamping members.

55 In use the drums are always rotated in the direction indicated by the arrow, which, 60 in this case, is a clockwise direction, but it will be understood that the direction of rotation is determined by the free ends of the spring members 43. The machine may be moved either forwardly or rearwardly 65 over the floor or other surface to be finished,

and as the spring members rotate the centrifugal force will tend to cause their movement outwardly and as they are brought into engagement with the floor a broad contacting surface results. This surface is also 70 broadened by the abutment of the free end 44 against the drum due to the pressure on the spring members 43.

75 It will be desirable from time to time as the abrasive power of the sand paper varies to adjust the tension of the spring members with respect to the floor and for this reason the rollers 12—12 may be adjusted by the movement of their supporting shaft by means of adjusting devices on each side 80 of the housing. As shown in Figure 5, each of these adjusting devices may consist of a set screw 55 operating in a bracket 56. The set screws 55 have an enlarged portion 57 operating in an opening 58 in the support 85 59. By the operation of the set screws 55 the desired position with respect to the floor can be obtained.

90 Although I have described my present invention in connection with a machine for sand papering floors I am aware that with slight modifications the same can be adapted for polishing and sanding other surfaces and can be used in finishing in a large variety of methods. 95

Having thus described my invention what I claim as new and desire to secure by Letters Patent of the United States is:

1. In combination, a support, rotatable means carried thereby, a fixture carried by the rotatable means, a spring member secured to said fixture and having a free end portion thereof pointing opposite the direction of rotation, padding disposed over the spring member, flexible material having abrasive material on its face and secured to said rotatable means, and clamping means arranged to hold the flexible material in place.

2. In combination, a support, rotatable means carried thereby, a spring member secured to said rotatable means, and having a free end portion thereof pointing opposite the direction of rotation, flexible material having abrasive material on its face and secured to said rotatable means, and clamping means to hold the flexible material in place.

3. An abrading element comprising a shaft, a pulley mounted on said shaft, a plurality of arcuate leaf spring members each having one end secured to said pulley and the other end free from said pulley, the free ends of said spring members being reversely curved on the inner sides of said spring members to form buffers between said 125 spring members and pulley, pieces of flexible material disposed on the free ends of said spring members and said pulley for limiting the outward movement of said spring members, and abrading material se- 130

cured to the outer sides of said spring members.

4. An abrading element comprising a shaft, a pulley mounted on said shaft, a plurality of arcuate leaf spring members each having one end secured to said pulley and the other end free from said pulley, pieces of flexible material disposed on the free ends of said spring members and said pulley for limiting the outward movement of said spring members, and abrading material secured to the outer sides of said spring members.

5. An abrading element comprising a shaft, a pulley mounted on said shaft, a plurality of arcuate leaf spring members each having one end secured to said pulley and the other end free from said pulley, flexible material for limiting the outward movement of said spring members, and abrading material disposed on the outer sides of said spring members.

6. In combination, a support, an abrading element mounted for rotation in said support, said abrading element comprising a drum, a flexible element secured at intervals to the periphery of said drum, abrasive material carried on the face of said flexible element, arcuate leaf spring members secured to the periphery of said drum and arranged to urge the flexible element away from the periphery of said drum to engage a surface to be abraded, said flexible element limiting the outward movement of said spring members.

7. An abrading element comprising a pulley, a flexible element loosely embracing the periphery of said pulley, means for clamping said flexible element at intervals to the periphery of said pulley, abrasive material carried on the outer face of said flexible element, spring means disposed at points intermediate said clamping means and secured to the periphery of said pulley and arranged to urge the flexible element away from the periphery of said drum to effect a resilient abrasive surface substantially as and for the purpose described.

8. An abrading element comprising a pulley, a flexible element loosely embracing the

periphery of said pulley, means for clamping said flexible element at intervals to the periphery of said pulley, said means comprising a bar provided with keyhole slots, abrasive material carried on the outer face of said flexible element, spring means disposed at points intermediate said clamping means and secured to the periphery of said pulley and arranged to urge the flexible element away from the periphery of said drum to effect a resilient abrasive surface substantially as and for the purpose described.

9. An abrading element comprising a pulley, a flexible element loosely embracing the periphery of said pulley, means for clamping said flexible element at intervals to the periphery of said pulley, abrasive material carried on the outer face of said flexible element, a plurality of arcuate leaf spring members each having one end secured to said pulley and the other end free from said pulley, the free ends of said spring members being reversely curved on the inner sides of said spring members to form buffers between said spring members and said pulley, to effect a resilient abrasive surface, substantially as and for the purpose described.

10. An abrading element comprising a pulley, a flexible element loosely embracing the periphery of said pulley, means for clamping said flexible element at intervals to the periphery of said pulley, said means comprising a bar provided with keyhole slots, abrasive material carried on the outer face of said flexible element, a plurality of arcuate leaf spring members each having one end secured to said pulley and the other end free from said pulley, the free ends of said spring members being reversely curved on the inner sides of said spring members to form buffers between said spring members and said pulley, to effect a resilient abrasive surface, substantially as and for the purpose described.

In witness whereof, I hereunto subscribe my name this 8th day of April, A. D. 1918.

CARL G. NORMAN.
